(57) **CLAIM**

The ornamental design for a paint brush with cap, as shown and described.

DESCRIPTION

FIG. 1 is a perspective view of a paint brush with cap showing my new design with the cap member in place; FIG. 2 is an exploded perspective view with the cap shown separated, the bristles depicted by means of broken lines being shown for illustrative purposes only and forming no part of the claimed design;

FIG. 3 is a front elevational view taken in the direction of arrows 3—3 in FIG. 1;

FIG. 4 is a rear elevational view taken in the direction of arrows 4—4 in FIG. 1;

FIG. 5 is a side elevational view taken in the direction of arrows 5—5 in FIG. 1, the opposite side being a mirror image thereof;

FIG. 6 is a bottom plan view taken in the direction of arrows 6—6 in FIG. 1; and,

FIG. 7 is a top plan view taken in the direction of arrows 7—7 in FIG. 1.
